TOY

Nettie Florence Grusenmeyer, San Francisco,
Calif.

Application January 15, 1944, Serial No. 518,334

1 Claim. (Cl. 46—105)

My invention relates to improvements in wheeled toys.

The object of my invention is to provide a simple inexpensive form of animated wheeled toy in which the rotation of the wheels as the toy is moved over a plane surface causes portions simulating wings to rise and fall; to provide foot simulating portions which will flap on the plane surface when the wing comes into its lowest position; to provide a wheel cart having the above features incorporated in the sides of the cart body; and to provide other features explained herein.

Pursuant to Rev. St. Sec. 4888 I shall describe and illustrate two forms of my invention, but it is not with the intention of limiting my invention to these particular forms or embodiments, except as required by the state of the art and the appended claims.

In the drawings,

Fig. 1 is a view in perspective of a wheeled cart embodying my invention;

Fig. 2 is a view of the same device from the rear;

Fig. 3 is a view in vertical cross-section taken 25 aft of the cart axle;

Fig. 4 is a view in perspective of a modification;

Fig. 5 is a view of the same device from the rear; and

Fig. 6 is a view in perspective of one form of connecting link.

Referring to the drawings and to the toy wagon illustrated in Fig. 1, this form of the invention includes the carrying platform 10 having a tail gate 11 and a dash board 12. These parts are secured to the side frame members 13 and 14 which are shaped to represent a side profile of some form of bird or other winged creature. These side frame members include the head portion 15, the under portion 16, and the back portion 17. The eye 18, bill 19, and other identifying marks of the particular bird are painted or otherwise represented on the sides 13 and 14 so as to carry out the general effect desired. In the base 16 of each side member is a hole 20 to receive the axle 21 on which the wheels 22 which support the cart or wagon are secured. As shown in Fig. 3, the carrying platform or floor 10 preferably is set in dado grooves cut in the side members 13 and 14. Between the lower section 16 and upper section 17 of each side member a flexibly mounted, winged simulating portion 30, is secured so that the winged portion 30 will hinge generally along its joint with the side members

13 and 14. These winged portions 30 may be of leather, paper, wood, or any other suitable material and are intended to simulate the wings of the particular bird represented by the side members 13 and 14. I have found a good way to secure these winged members 30 to the sides is to cut a slot 31 part way along the back of the bird at a thickness adapted to receive the winged member when it is inserted. A few brads securely lock it in the slot. The wing members 30 are adapted to flap up and down, and this movement is imparted to them by means of a link 33 pivoted at 34 to each wheel 22 and loosely secured at 35 to the wing member 30 by means of the headed screw or tack 36. The connection to the wheel at 34 may be by a small nail 37 which will allow the link 33 sufficient oscillating movement to flex outwardly as it moves upwardly into the position shown in the right in Fig. 3. A detail of one form of this link member 33 is shown in Fig. 6 having the foot simulating portion 40 which may be of paper, thin rubber, leather, or other suitable material glued or secured in a slot 41 in the bottom end of link 33. In lieu of such a slot, the foot simulating portion 40 may be tacked to the bottom end of link 33. As shown in Fig. 1 this foot simulating portion 40 will flap on the plane surface when the link approaches its lowest point of travel.

20 The device so far described thus includes the carrying platform 10, the pair of spaced apart side members 13 and 14 to support this platform, said side members being shaped to simulate the body of a winged fowl, an axle shaft 21 journaled in these side members, wheels 22 secured thereon, hingedly mounted wing simulating portions 30 extending over the outside edge of each side member 13 and 14, a link 33 pivoted to each wheel 22 and secured at 35 to the adjacent winged portion 30 and a hingedly mounted foot simulating portion 40 secured to each link 33 adjacent its lower end. A handle 50 may be secured to the front of the wagon. As the wagon is pulled along a plane surface the rotation of the wheels will cause the winged members 30 to rise and fall and the foot members 40 to flap on the plane surface each time they come into their lower positions. The effect is of a pair of fowl, such as ducks, supporting between them a wagon body. As shown in the drawings the pins 37 connecting the links 33 to their respective wheels are set at 180° in respect to each other so one is down when the other is up and vice versa. This is a preferred setting because it gives the effect, in the case of a duck, of a waddling action. It is not

essential, however, because in the case of certain fowl the simultaneous rise and fall of the wings may be desirable.

Turning now to Fig. 4, the same principles of the invention are applicable. Here the toy includes a combination of a body member 60 in the shape of a winged bird, with a shaft 61 journaled therein having a wheel 62 secured to each end of the shaft, a flexible member 63 secured to the body member 60 with the wing simulating portions 63 overlying each wheel 62, a rod 33 pivotally connected at 34 to each wheel and loosely connected at 65 to the winged portions 63, and flexible members 40 simulating foot portions secured adjacent the lower end of each rod 33. As shown in Fig. 5, when the links 33 are pivoted to the wheels 62 at 180° pivot points, the effect is for one wing 63 to be up when the other is down. This toy is pulled around by a string 70.

What I claim is:

In a toy, the combination of a body member shaped like a bird; a pair of wheels rigidly secured to a common axle rotatably journaled in

said member and supporting said body when it is rolled over a plane surface, each of said wheels having a stub shaft set in its outer face, the stub shaft on one wheel being substantially 180° offset radially from the other; a flexible continuous sheet member simulating a pair of wings secured to said body member and extending outwardly therefrom on each side over said wheels; a pair of upstanding generally cylindrical members, each simulating a leg of the bird, each cylindrical leg member having a flexible sheet member secured at its lower end so as to simulate a flapping web-foot, a connection at its upper end to the flexible sheet member simulating the wing, and a pivoting means part way up the leg to connect with the stub shaft on the wheel adjacent it; whereby, as the wheels rotate, one cylindrical leg member lifts its connected wing and web-foot and then flaps it down while the other leg member is doing the reverse, to simulate the bodily gyrations of a waddling type of short-legged bird.
